UNITED STATES PATENT OFFICE.

KENNETH L. EDDY, OF CHICAGO, ILLINOIS, ASSIGNOR, BY MESNE ASSIGNMENTS, TO
AUTOMATIC UTILITIES CO., A CORPORATION OF ILLINOIS.

LOOSE-LEAF DEVICE.

1,211,690.

Specification of Letters Patent.

Patented Jan. 9, 1917.

Application filed March 20, 1914. Serial No. 825,947.

To all whom it may concern:

Be it known that I, KENNETH L. EDDY, a citizen of the United States, residing at Chicago, in the county of Cook and State 5 of Illinois, have invented a certain new and useful Improvement in Loose-Leaf Devices, of which the following is a specification.

My invention relates to that class of devices which are designed to lift a card or 10 group of cards above their normal plane, by the use of a device comprising a longitudinally movable bar, which is suitably connected by means of toggles to a rising bar, which is designed to engage pins de- 15 pending from the lower edge of the cards in the box or casing.

In devices of this character, it has been found difficult to obtain the necessary lift or elevation of the cards within the space 20 provided in the ordinary card index device. This has resulted in the lowering of the angle between the two pivoted points of the toggles to such an extent that it is very difficult to move the longitudinally movable 25 bar by the pressure of one's thumb at the first part of the movement. As soon as it is moved slightly, so as to vary the angle, it then raises easily.

My invention has for its object to provide 30 means which will overcome this difficulty and which will permit of the rising bar lying flat against the longitudinally movable bar and yet will insure its raising easily during all portions of its movement.

My means of accomplishing the foregoing 35 objects may be more readily understood by having reference to the accompanying drawings, which are hereunto annexed and are a part of this specification, in which:

Figure 1, is a fragmentary sectional view 40 of a card index casing, provided with a device of this character equipped with my improvements. Fig. 2, is an enlarged fragmentary detail view showing a modified 45 form of applying my invention. Fig. 3, is a top or plan view of a card index device.

Similar reference numerals refer to similar parts throughout the entire description.

As shown in the drawings, 1 is a casing 50 which is provided with forward and rear end walls 2 and 3 respectively. A longitudinal bar 4, the forward end 5 of which extends upwardly and is projected out-

wardly through the wall 2 is provided with a push button 6 of suitable size and shape. 55 The rising bar 7, which is secured to the longitudinally movable bar 4, by means of toggles 8 and 9, serves to raise the cards.

A roller 10, is carried by the end of the rising bar 7, and is designed to minimize 60 the friction caused by the pressure of the end of the rod against the metal guide plate 11, secured to the rear wall 3 of the casing 1. It has been formerly the custom in all devices with which I am familiar, to have 65 this guide plate flat, which resulted in the difficulty heretofore set out. I have discovered if its lower edge is curved as at 12, or inclined as shown in the modified form at 13, that this serves to relieve the strain, by 70 overcoming the nearly straight angle between the pivots 14 and 15 of the toggles 8 and 9, with a result that the rising bar 7 starts on its upward movement with the utmost freedom and without the slightest 75 difficulty, even when the bars 4 and 7 lie flat against each other, as shown in Fig. 2.

Although I have shown the device in connection with the structure shown in my co-pending application, bearing Serial No. 80 825,948, filed March 20, 1914, it is obvious that I do not desire to be limited to the said combination, but that my invention may be employed in any device of this character.

Having described my invention what I regard 85 as new and desire to obtain by Letters Patent is:

1. In a card index, a case, cards arranged in groups, a rising bar to lift the cards of the respective groups, a roller mounted in 90 the inner end of said rising bar, a guide plate for said roller having its lower edge bent inwardly for the purpose set forth substantially as described.

2. In a device of the character described 95 the combination with a casing having a plurality of cards therein, a rising rod for displacing one or more cards from their normal position, a roller mounted in the inner end of the rising rod, with a guide for said 100 roller consisting of a metal plate the lower end of which is bent inwardly for the purpose set forth substantially as described.

3. In a device of the character described 105 the combination with a casing having a plurality of cards therein, a rising rod for dis-

placing one or more cards from their normal position, a roller mounted in the inner end of the rising rod, with a guide for said roller consisting of a metal plate, the lower edge of said plate being curved inwardly, for the purpose set forth substantially as described.

In witness whereof, I have signed the foregoing specification.

KENNETH L. EDDY.
